CLAIM

The ornamental design for a box, as shown and described.

DESCRIPTION

FIG. 1 is a front perspective view of a first embodiment of the present invention, a rear perspective view being identical thereof.

FIG. 2 is a front elevation view of FIG. 1.

FIG. 3 is a rear side elevation view of FIG. 1.

FIG. 4 is a top plan view of FIG. 1.

FIG. 5 is a bottom plan view of FIG. 1.

FIG. 6 is a left side elevation view of FIG. 1.

FIG. 7 is a right side elevation view of FIG. 1.

FIG. 8 is a front perspective view of a second embodiment of the present invention, a rear perspective view being identical thereof.

FIG. 9 is a front elevation view of FIG. 8.

FIG. 10 is a rear side elevation view of FIG. 8.

FIG. 11 is a top plan view of FIG. 8.

FIG. 12 is a bottom plan view of FIG. 8.

FIG. 13 is a left side elevation view of FIG. 8; and,

FIG. 14 is a right side elevation view of FIG. 8.

The broken lines illustrating the edges of the article depict portions of the box that form no part of the claimed design. The present invention are boxes with an ornamental indicia on the side thereof.

1 Claim, 8 Drawing Sheets
